Attorney

UNITED STATES PATENT OFFICE.

LEWIS W. NORRIS, OF OAKLAND, CALIFORNIA.

WELL-BORING DEVICE.

1,427,410.

Specification of Letters Patent. Patented Aug. 29, 1922.

Application filed August 31, 1920. Serial No. 407,148.

To all whom it may concern:

Be it known that I, LEWIS W. NORRIS, a citizen of the United States, residing at Oakland, in the county of Alameda and State of California, have invented certain new and useful Improvements in Well-Boring Devices, of which the following is a specification.

My invention is an improved well drill 10 rig.

Referring to the annexed drawing in which my invention is illustrated and which forms a part of this specification,

Figure 1 is a front elevation of my rig 15 with the drill gripping parts in their uppermost position holding the drill elevated.

Figure 2 is a view similar to Figure 1 with the drill gripping parts in their lowermost position and about to grip and elevate the 20 drill.

Figure 3 is a transverse vertical section of the rig taken on line 3—3 of Figure 2.

Figure 4 is an enlarged plan view of one 25 of the drill gripping levers and jaws.

Figure 5 is an enlarged side view of said gripping lever and jaw.

In the drawing, 1 indicates a base on which are bolted standards 2, 3, 4, 5, 6, 7, 8 and 9 in which are guideways 10. On the 30 front of said standards are bolted bearings 11, 12, 13, 14, 15, 16, 17 and 18 respectively, in which is journaled a horizontal crank shaft 20 having cranks 21, 22, 23 and 24 located respectively between the standards 2 35 and 3, 4 and 5, 6 and 7, and 8 and 9. The cranks 22 and 23 extend from the shaft 20 at the same angle while the cranks 21 and 24 also extend from the shaft at the same angle but in advance of the cranks 22 and 40 23. A cross head 25 is slidably mounted in the guideways 10 of the standards 2 and 3. A crosshead 26 is slidably mounted in the guideways 10 of the standards 4 and 5. A 45 crosshead 27 is slidably mounted in the guideways 10 of the standards 6 and 7. A crosshead 28 is slidably mounted in the guideways 10 of the standards 8 and 9. A pitman 29 connects the crank 21 and the crosshead 25. A pitman 30 connects the 50 crank 22 and the crosshead 26. A pitman 31 connects the crank 23 and the crosshead 27. A pitman 32 connects the crank 24 and the crosshead 28. A gripping lever 35 is pivoted at 36 and 37 to the upper part of the crossheads 25 and 26. A gripping lever 40 is pivoted at 41 and 42 to the crossheads 27

and 28. The base 1 is provided with an opening 43 between the standards 5 and 6 through which opening the drill 45 extends into the ground and a plate 46 is bolted to the top of the standards 5 and 6 through which the drill extends. On the ends of the gripping levers 35 and 40 are pivoted drill gripping jaws 50 and 51 respectively. Each jaw includes a pivoted supporting member 52 and a gripping member 53. The member 52 of each jaw has a pair of spaced ears 54 which fit over the ends of the gripping levers 35 and 40 and are pivoted thereto by pivot pins 55. The members 52 also have vertical flanges 56 and the members 53 have vertical flanges 57 which rest against the flanges 56 and are riveted thereto by rivets 58 whereby the members 53 are detachably secured to the members 52. The gripping faces of the jaw members 53 have vertical semi-circular grooves 59 adapted to fit the drill 45 at opposite sides. On the top of each jaw member 52 is a lug 60 and lugs 61 extend from the upper side of the levers 35 and 40. An expansion spring 65 is interposed between each lug 60 and a lug 61. A horizontal plate 70 extends between the standards 5 and 6 and is secured to angle irons 71 which are secured to said standards, the drill 45 extending through an opening in said plate. Dogs 72 and 73 are pivoted to the upper side of said plate so that they may be swung into and out of engagement with the drill. The dogs are thrown into engagement with the 75 drill to hold the drill elevated. A gear 75 is secured to one end of crank shaft 20 to which gear power is applied to rotate the shaft. A fly wheel 76 is secured on the other end of said crank shaft. An arm 80 is secured to the shaft for engaging the drill 45 at each revolution and turning the drill. 80

When the cranks 21, 22, 23 and 24 move upwardly, the cranks 21 and 24 moving in advance of the cranks 22 and 23 swing the 85 jaw ends of the levers 35 and 40 downwardly on their pivots 37 and 41 and cause the jaws 50 and 51 to grip the drill 45 and elevate the same. When the drill has been elevated, the cranks 21 and 24 moving downwardly ahead 90 of the cranks 22 and 23 swing the jaw ends of the levers 35 and 40 upwardly on pivots 37 and 41 and cause the jaws 50 and 51 to release the drill 45, which drops by gravity. The arm 80 engages the drill 45 and turns it 95 while the drill is released and in its lowermost position. On the downward movement 100

105

of the jaws 50 and 51 the springs 65 swing the jaws downwardly so that their lower edges do not bind and hold up the drill.

Having described my invention, I claim:

5 1. A well drill rig including a pair of gripping levers, jaws on the ends of said levers adjacent the drill, two slidably mounted cross heads on which each lever is pivoted, a crank shaft formed with four cranks, a 10 pitman connecting each cross head with one of said cranks, two of said cranks extending at an angle in advance of the other two cranks whereby said levers are swung to cause said jaws to grip and elevate the drill 15 and to cause the jaws to release the drill when elevated.

2. A well drill rig including a pair of levers, jaws on said levers for gripping the drill, a crank shaft, means actuated by said 20 crank shaft for swinging said levers to cause said jaws to grip and elevate the drill and

to release the drill when elevated, and an arm secured on said crank shaft for engaging and turning said drill.

3. A well drill rig including a pair of 25 levers, jaws on said levers for gripping the drill, a crank shaft, means actuated by said crank shaft for swinging said levers to cause said jaws to grip and elevate the drill and 30 to release the drill when elevated, and springs for urging said jaws downwardly so that the lower edges of the jaws will not bind on the drill when the jaws have elevated the drill and said levers swung to release the jaws.

4. A jaw made in two parts, one part being formed with a gripping surface, flanges on each part, and means for securing the flanges of one part to the flanges of the other part.

In testimony whereof I affix my signature.

LEWIS W. NORRIS.
